UNITED STATES PATENT OFFICE

HEINRICH REICHMANN, OF DUISBURG, GERMANY

GRAB

Application filed January 30, 1930, Serial No. 424,503, and in Germany June 14, 1928.

My invention relates to devices for gripping scrap, ores, stones or other articles, and has for its object to provide a device of this character which will be particularly adapted 5 to handle, without injury to the apparatus, stones or other material of relatively large size or great hardness. The accompanying drawings illustrate my invention in connection with lifting devices of the type disclosed 10 in my application for Letters Patent of the United States filed March 9, 1928, Serial No. 260,269. The device includes gripping or holding arms or jaws fulcrumed on a carrier and also pivotally connected with pressure 15 rods, and according to my present improvement at least one of said joints or connections (fulcrum joint and connection with the pressure rod) is constructed as a universal joint giving the parts great freedom of motion.

Reference is to be had to the accompanying drawings, in which Fig. 1 is an elevation showing one embodiment of my invention, this view being fragmentary in that it shows a single pair of holding jaws, whereas in 25 practice several pairs are generally employed, for instance after the fashion shown in Fig. 6; Fig. 2 illustrates separately, in elevation and upon a larger scale than Fig. 1, two members which constitute a fulcrum 30 bearing for one of the holding jaws; Fig. 3 is a top view of one of said bearing members; Fig. 4 is a fragmentary elevation, with parts in section, illustrating another embodiment of my invention, this view, like Fig. 1, showing only one of the several pairs of jaws 35 which the lifting device comprises generally; Fig. 5 is a detail elevation showing the lower end of the pressure rod employed in this second embodiment of my invention; and 40 Fig. 6 is a bottom view of the construction shown in Fig. 4, with parts broken away.

In Figs. 1, 2, and 3, I have shown an upper box or carrier 1 and a lower box or carrier 2. The lifting rope or cable 3 is connected with 45 the upper carrier 1, to raise or lower the entire apparatus in any well-known or approved manner, while the jaw-controlling rope or cable 4 (operated by any customary or approved mechanism) passes in contact 50 with rollers 5 and 6 journaled in the upper

carrier 1 and in the lower carrier 2 respectively. To the upper carrier are pivoted at 9, the pressure bars or rods 7 the lower ends of which are connected loosely at 10 with the holding jaws or grippers 8, arranged in 55 pairs. For the sake of simpler illustration, a single pair of grippers is shown in Fig. 1 (and Fig. 4), but in practice I will generally employ a plurality of such pairs, for instance four pairs, as indicated in Fig. 6. 60 The grippers are fulcrumed on the lower carriage 2.

The joints 10 connecting the grippers 8 with the pressure rods 7 are ball and socket joints in the construction illustrated by Figs. 65 1, 2, and 3, and the fulcrum connections of said grippers with the lower carrier 2 are made as universal joints, and preferably as ball-and-socket joints. For this purpose, the fulcrum ends of the grippers 8 are shown 70 as made with balls 11 fitted into sockets formed in the adjacent faces of socket members 12 and 13. While these socket members are separated, the balls 11 are introduced between them, then the upper member 13 is 75 lowered into contact with the lower member 12, and both members are secured to the lower carrier 2 in any suitable manner. As shown in Fig. 1, the lower member 12 is preferably in the form of a flange integral with 80 the lower carrier. As will be seen in Figs. 2 and 3, the lower socket member 12 has a cut-out portion 12^a giving the fulcrum end of the gripper 8 sufficient vertical and lateral play to enable the gripper to adjust itself to 85 the article to be held and lifted or lowered.

The provision of universal joints at the lower ends of the pressure rods is also shown in the embodiment of my invention illustrated by Figs. 4, 5, and 6. The upper carrier 15 is connected with the lifting rope or cable 3, while the gripper-controlling rope or cable 4 engages the pulleys 5 and 6 journaled in the upper carrier 15 and in the lower carrier 16 respectively. The lower ends of the pressure rods 17 are connected loosely with the grippers 18, and the lower portion of the lower carrier 16 is formed with the upper halves 19 of sockets in engagement with the balls 20 at the fulcrum ends of the grippers 100

18. The lower halves 21 of these sockets are formed on the upper surface of a holding-member 22, secured in position by bolts and nuts 23, or any other suitable means. This 5 construction enables the fulcrum joints of the grippers to be placed close to the center or vertical axis of the device, and this is desirable since the grippers will then close with greater force and will also grip the material 10 more powerfully. A plug 24 fitted into suitable central sockets of the lower carrier 16 and of the holding member 22, serves to insure the proper centering of these parts.

The loose connection at the lower ends of 15 the pressure rods 17 is also in the nature of a universal joint, to enable the grippers and said rods to adjust themselves more readily to material of large size and great hardness. Here too I prefer to employ a ball-and-socket joint, as by providing balls 25 on 20 the grippers 18, and companion forked sockets 17^a at the lower ends of the rods 17. Simple horizontal pivots 26 will suffice for a satisfactory connection between the upper carrier 1 25 and the upper ends of the pressure rods 17, since the length and the yielding or elastic character of these rods will give them sufficient flexibility; still, if desired, universal joints might be provided at said upper ends 30 also.

Instead of ball-and-socket formations, I 35 may employ any other well-known or approved type of universal joint, such as hook joints or spring joints, as long as the desired function is obtained, which consists in enabling the grippers not only to swing in vertical planes, but to move laterally and also to have a limited turning or twisting movement about an axis connecting the fulcrum of 40 a gripper with the point at which the lower end of the pressure rod is attached to said gripper.

It will be understood that before the grippers are brought into engagement with the 45 article to be held, the lower carrier is dropped or moved away from the upper carrier, so that the pressure rods will cause the grippers to swing open, see the position indicated by dotted lines at the right of Fig. 4. With the 50 grippers in this position, the entire device is lowered until the grippers are immediately above the article or material to be seized. Then, by an upward pull on the cable 4 while the upper carrier remains stationary, the lower carrier is moved up toward the upper carrier, bringing the parts to the position shown 55 in Figs. 1 and 4, and causing the grippers to close upon the article to be seized. Thereupon an upward pull is exerted on the cable 3 60 while continuing the upward pull on the cable 4, and thus the entire device is lifted together with the material held by the closed grippers. When the material has been brought to the 65 spot where it is to be released or deposited, the pull on the cable 4 is discontinued while the

cable 3 is kept under tension, and the weight of the material and of the lower carrier will cause the latter to move downward relatively to the upper carrier, whereby the grippers will be caused to swing to the open or releasing position.

It will be understood that the two embodiments illustrated are simply typical examples of my invention, and that various modifications may be made without departing from the nature of my invention as set forth in the appended claims.

I claim:

1. A device of the class described, comprising an upper carrier, a lower carrier movable toward and from said upper carrier, grippers having one set of joints connecting them loosely with the lower carrier, and also having another set of joints, the last-mentioned joints being of a ball and socket type, and connecting members extending from the upper carrier to the grippers at the ball and socket joints thereof.

2. A device of the class described comprising an upper carrier, a lower carrier movable toward and from said upper carrier, said lower carrier having a flange provided with a plurality of upwardly open sockets associated therewith, grippers having ball portions engaging said sockets, holding members having downwardly open sockets therein secured to said carrier and registering with the first said sockets to hold said ball portions in said sockets, said grippers having shanks connecting them with said ball portions, said first named sockets having vertical slots therein of greater width than the thickness of said shanks, and connecting members connected to said grippers and said upper carriers.

In testimony whereof I have hereunto set my hand.

HEINRICH REICHMANN.
